PROCESS OF MANUFACTURING BIMETALLIC APPENDICES FOR MONOMETALLIC BALANCES

Paul Ditisheim, Paris, France

Application March 26, 1932, Serial No. 601,426
In Switzerland April 2, 1931

10 Claims. (Cl. 29—178)

The present invention relates to a process of manufacturing bimetallic appendixes for monometallic balances combined with a spiral made of an alloy called Elinvar.

5 The complicated composition of the Elinvar, the difference of the densities and of the melting points of its components and also the difference of its homogeneity resulting partly from the wire-drawing process, from the rolling and from the 10 shaping of the spirals are as many items which influence the compensating qualities of a spiral made of said alloy. In order to amend the defects of the different casting processes and the discrepancies between one spiral and another 15 turned out by the same casting process it has been proposed to combine with spirals of Elinvar monometallic balances having a suitable linear dilatation and to which according to the established discrepancies compensating bimetallic bodies have 20 been fixed either on the inside or on the outside of the rim.

The compensating fixtures used heretofore have been manufactured according to the process employed for the split bimetallic compensating 25 balances. In a perforated steel disk a very deep furrow was cut which was filled with brass. Then the bimetallic cylinder thus obtained was turned on its inside and on its outside to obtain the desired thicknesses of metal. From such a ring 30 generally six fixtures were cut out, or rather three pairs of a given curvature as obtained by the turning process.

It is certain that such fixtures were rather expensive and therefore the manufacture of this 35 kind of compensating fixtures was hindered very much.

The object of the present invention is a manufacturing process of bimetallic fixtures or appendixes for monometallic balances combined 40 with spirals made of Elinvar which leads easier and at a less expense to the desired result.

The starting body for this new process is a bimetallic body having a very extended plane 45 surface. The fixtures are cut out from such a body either by a press, a saw, or any other means and are bent to the desired curvature. The bimetallic band may be rolled helicoidally around a cylinder having the desired curvature and by 50 a repeated reheating the molecular stabilization is assured. Then the helicoidal band is cut up into the several fixtures and before finishing these latter the holes for the fixing screws have been drilled and the holes for the compensating screws 55 generally used with such members.

The annexed drawing shows, as far as it is required for understanding the process according to the present invention, one way of proceeding for obtaining fixtures or appendixes according to the new process.

60 The Figures 1 and 2 show the way heretofore followed for manufacturing bimetallic appendixes.

The Figures 3 and 4 show the new way for obtaining the same appendixes, and

65 The Fig. 5 represents a bimetallic band, the cross section of which is shown in Fig. 6 while the Fig. 7 shows a drum around which said bimetallic band has been wound for giving to the appendixes the desired curvature.

70 With reference to the Figures 1 and 2 of the annexed drawing *a* is a steel disk having a very deep furrow *b* which is filled with borax and on which a brass ring *c* has been deposited. The whole is put into the fire until the brass has melted and has filled the furrow completely. The bimetallic cylinder thus obtained has to be turned in order to obtain a bimetallic ring *d* (Fig. 2) into the periphery of which the required holes for the fixing screws are drilled and the holes for holding the compensating screws. By means of such a bimetallic ring six appendixes may be obtained having a given curvature. This is the old manufacturing process.

75 In the process according to the present invention a bimetallic band *e* is prepared, such as shown in the Figs. 5 and 6, by plating the two metals one upon the other or by galvanizing one metal upon the other: such a band may also be obtained by casting one metal upon the other or by uniting the two metals by a wire-drawing or a rolling process. A bimetallic band is called here a band composed of two metals having different coefficients of dilatation so that when the band is held fixed at one end the band will bend 80 to one side or the other according to the changes of temperature of the circumambient medium to which it has been submitted.

85 As said band is perfectly plane and has the desired dimensions the holes for the fixing screws and for the compensating screws may be drilled 90 at the desired distances. Then the whole may be wound around a drum as shown in Fig. 4 the curvature of which corresponds with that of the rim of the balance which is to be provided with 95 the manufactured appendixes. One end of the band will be fixed to the drum before the winding, and after the winding the other end of the band will be fixed likewise. After this the molecular stabilization will be assured by any of 100 105 110

the reheating processes known in metallurgy.

By the process it is possible to wind at wish the most dilatable metal around the inside or the outside according to the effect of the thermic variations in advance or in slowness which have to be taken into account.

After having withdrawn the helicoidal band thus formed from the drum by displacing the band in an axial direction this band may be 10 cut up into the number of appendixes which are desired. This proceeding may be accompanied by a polishing of the surfaces.

Then the appendixes thus formed are fixed according to the Fig. 3 or the Fig. 4 to the monometallic balances so as to correct the defects connected with a given Elinvar spiral. That is to say, as in the case of the Fig. 3, that the screws *f* shall become approached to the rim *g* when the temperature is rising or that said 20 screws, as in the case of the Fig. 4, shall be removed from the rim *g* likewise when the temperature is rising.

By choosing dilative metals of more or less divergences it is possible to obtain at wish more or less important corrections for the advance or for the slowness. It is also possible to arrange the appendixes so that nonmagnetic metals are used or metals which do not keep up some remnant magnetism.

30 What I claim is:

1. A method of making compensating balances that include a monometallic wheel used with a hairspring of Elinvar which includes the acts of first forming a bimetallic body in an extended flat form of an area from which a number of such attachments may be cut thereafter cutting pieces from such body of the required dimensions for an attachment, curving the pieces in correspondence with the curvature of the balance rim to which they are to be attached, and attaching the same to the monometallic wheel.

2. A method of making bimetallic compensating attachments for monometallic balances used with a hairspring of Elinvar which includes the acts of first forming a bimetallic body in an extended flat form of an area from which a number of such attachments may be cut, curving such body in correspondence with the curvature of the balance rim to which it is to be attached, and thereafter cutting pieces from such body of the required dimensions for an attachment.

3. A method of making compensating balances that include a monometallic wheel used with a hairspring of Elinvar which includes the acts of first forming a bimetallic body in an extended flat form of an area from which a number of such attachments may be cut, performing upon such body the operations required to fit it for its use as an attachment, and thereafter cutting pieces from such body of the required dimensions for an attachment and attaching the same to the monometallic wheel.

4. A method of making bimetallic compensat-

65

70

75

ing attachments for monometallic balances used with a hairspring of Elinvar which includes the acts of first forming a bimetallic body in an extended flat form of an area from which a number of such attachments may be cut, giving such body a helical form of a curvature corresponding with the curvature of the balance with which the attachment is to be used, and thereafter cutting pieces from such body of the required dimensions for an attachment.

5. A method of making compensating balances that include a monometallic wheel used with a hairspring of Elinvar which includes the acts of forming a straight band of united layers of metal, the surfaces of the band being plane and thereafter cutting such band into a number of pieces each of a suitable length for attachment to a balance wheel, curving the pieces in correspondence with the curvature of the balance rim to which they are to be attached, and attaching the same to the monometallic wheel.

6. A method of making bimetallic compensating attachments for monometallic balances used with a hairspring of Elinvar which includes the acts of forming a straight band of united layers of metal, the surfaces of the band being plane, giving to such body a curvature in correspondence with the curvature of the balance with which the attachment is to be used, and thereafter cutting such band into a number of pieces each of a suitable length for attachment to a balance wheel.

7. A method of making balance wheels used with a hairspring of Elinvar which includes the steps of making a bimetallic body of metals that have a compensating relation, of plane form of extended length, curving such body into correspondence with the curvature of the rim of a monometallic balance, cutting such body into lengths suitable for attachment to a monometallic balance, and then attaching such a length at one end to a monometallic balance.

8. A method as in claim 2 in which after the step of curving the body, the same is subjected to heat treatment to produce molecular stabilization.

9. A method as in claim 7 in which after the step of curving the body, the same is subjected to heat treatment to produce molecular stabilization.

10. A method of making balances that includes the acts of providing a mono-metallic wheel for use with a hairspring requiring temperature compensating attachments, forming a bi-metallic body in an extended flat form of an area from which a number of such attachments may be cut, thereafter cutting pieces from such body of an angular extent substantially less than the circumference of the mono-metallic wheel, curving such piece in correspondence with the curvature of the balance rim before such piece is cut therefrom, and then attaching such piece to the balance circumference with a substantial portion of the piece free from the wheel.
